UNITED STATES PATENT OFFICE.

WILLIAM GILBERT TERWILLIGER, OF HIGHLAND, NEW YORK, AND JOHN SCUDDER,
OF BROOKLINE, MASSACHUSETTS.

CARTON.

Application filed April 28, 1924. Serial No. 709,093.

This invention relates to a novel form of carton which is provided with a convenient means of opening the same whereby upon opening ready access may be had to the contents.

The invention is more particularly directed to cigarette cartons of the wrapped type in which provision is made for completely severing one side and the two edges of the 10 carton by means of suitable tearing strings. The carton when thus opened readily hinges about the unsevered side and thereby affords to the user the convenience of the usual card cigarette box with hinged cover and at the 15 same time greatly reduces the cost of the carton to the cigarette manufacturer.

At the present time the wrapped type of carton has come into general use for cigarettes and the general practice is to open such 20 cartons at one end. Occasionally users open the cartons at the side to obtain lateral access to the cigarettes but to open the cartons in this manner is at best very troublesome.

According to the present invention an extremely convenient means is provided for opening the cartons so as to give lateral access to the contents thereof.

In the drawings,

Fig. 1 is a perspective view of the complete carton in closed condition.

Fig. 2 shows the carton fractured by drawing upon the tearing strings.

Fig. 3 shows the carton in open position hinged about the unsevered side so as to give lateral access to the contents.

Fig. 4 is a sectional view taken on line 4-4 of Fig. 1.

Fig. 5 is a sectional view taken on line 5-5 of Fig. 4.

The carton is of the type now extensively utilized in connection with the sale of cigarettes and the like. The carton comprises an inner oil paper lining 10 next to which is disposed a foil lining 11 and without the foil lining there is the usual outer paper wrapper 12.

In order to provide a means for rupturing the carton a tearing string 13 is provided. This tearing string, as will be seen from Fig. 4, is disposed within the inner paper lining 10 at the top of the carton and at

the sides and bottom it is disposed between the paper lining 10 and the foil material 11.

The tearing string is brought out through an aperture in the top of the carton and terminates in two ends 14. By grasping these two ends and pulling in opposite directions it is possible to fracture the top and sides of the carton whereupon it will appear as in Fig. 2 of the drawings. Subsequently the two halves of the carton may be opened up, the composite material 10, 11 and 12 of the carton on the unruptured side serving as a hinge and permitting ready access to the contents. Fig. 3 shows the 65 carton opened up in this manner.

What we claim is—

1. A cigarette carton including foil and paper wrappings and having in combination therewith a tearing string disposed between the foil and paper wrapping at one side of and at the ends of the carton, said string being disposed within all of the wrappings at the opposite side of the carton and having its ends passing through an opening in said side whereby said side and the two edges of the carton may be fractured by drawing upon the string to permit the carton to be opened by bending said unruptured side as a hinge.

2. A cigarette carton including foil and paper wrappings and having a tearing string in combination therewith, said tearing string disposed between the foil and paper wrappings at one side of and at the ends of the 85 carton, said tearing string upon the other and opposite side being disposed inside all of the wrappings including the inner foil layer and having its ends upon said opposite side passing through an opening in said side and adapted to rupture the said opposite side of the carton and the two end edges and leave the side in which the tearing string is embedded between the foil and paper wrappings unruptured so that it may serve 95 as a hinge substantially about the tearing string as an axis and leave the cigarettes disposed in accessible position in both hinged halves of the carton.

In testimony whereof we hereto affix our signatures.

WILLIAM GILBERT TERWILLIGER,
JOHN SCUDDER.
